UNITED STATES PATENT OFFICE.

EDMUND CURRAN, OF BOSTON, MASSACHUSETTS, ASSIGNOR, BY MESNE ASSIGNMENTS,
TO NATIONAL MACHINERY CORPORATION, OF BOSTON, MASSACHUSETTS, A COR-
PORATION OF DELAWARE.

LACING-HOOK-SETTING MACHINE.

1,121,327.

Specification of Letters Patent. Patented Dec. 15, 1914.

Application filed January 30, 1913. Serial No. 745,153.

To all whom it may concern:

Be it known that I, EDMUND CURRAN, of Boston, in the county of Suffolk and State of Massachusetts, have invented certain new and useful Improvements in Lacing-Hook-Setting Machines, of which the following is a specification, reference being had to the accompanying drawings, forming part thereof.

10 This invention has reference to an improved machine for setting or securing lacing hooks or studs to shoes.

One object of the invention is so to construct a machine of this nature that lacing 15 hooks or studs simultaneously may be secured to both sides or edges of a shoe upper.

Another object of the invention is so to construct a machine of this nature that the shoe upper may, during operations, be supported 20 in a vertical position with the edges of the shoe upper in position convenient for inspection during such operation.

Another object of the invention is to facilitate the adjustment of the machine for 25 operation on shoe uppers of various sizes.

Another object of the invention is to facilitate the starting of the machine.

Other objects of the invention will appear from the following description.

30 The invention consists in the novel features of construction and combination of parts hereinafter described and pointed out in the claims.

Referring to the drawings:—Figure 1, 35 represents a plan view, partly in section and with parts broken away, of a machine embodying my invention. Fig. 2, represents a front view, partly in section, and with parts broken away of same. Fig. 3, represents a fragmentary sectional view, partly in elevation, on the line 3—3 of Fig. 1. Fig. 4, represents a sectional view, partly in elevation and with parts broken away, on the line 4—4 of Fig. 1. Fig. 5, represents a 45 sectional view, partly in elevation, on the line 5—5 of Fig. 1. Fig. 6, represents a fragmentary end elevation of the die holder and clamping mechanism, with a section of a shoe upper clamped in position ready to receive the hooks. Fig. 7, represents a fragmentary plan view of the portion of the machine represented in Fig. 6, with the clamp open. Fig. 8, is a fragmentary sectional view, partly in elevation, on the line 8—8 50 of Fig. 1. Fig. 9, represents a fragmentary

sectional view partly in elevation on the line 9—9 of Fig. 8.

Like reference characters designate corresponding parts throughout.

In the machine represented in the drawing, which is a preferred form of my invention, 10 represents the main shaft which is journaled in suitable bearings 11 on the frame 12. Loosely mounted on said shaft is a driving pulley 13 which is provided with 60 sockets 14 and fixed to said shaft, adjacent said pulley, is a clutching member 15. The latter is provided with a spring pressed plunger 16 which normally engages one of said sockets. Said plunger is provided with 65 the cam surface 17 which is adapted to be engaged by a corresponding cam surface 18 near one end of the lever 19. The latter is pivoted on the pin 20 which is supported by brackets 21 projecting upwardly from 70 the base of the frame 12. On the lower end of said lever is pivoted the lever 22, the rear arm 23 of which, is adapted to be engaged by the lug 24 projecting from the clutch member 15 and its other arm 25 is normally 75 held in engagement with the pin 26 by a spring 27. Said pin 26 is fixed to the arm 28 which is pivoted on the pin 20 and is normally pressed against the stop 29 by the leaf spring 30. Through the lower end of 80 said arm is threaded the set screw 31 which is adapted to be engaged by the rear end of the shaft 32. The rear portion of said shaft extends through the miter gear 33 and is substantially square in cross section, so 85 that it is adapted to reciprocate in and to rotate said miter gear. The shank of the latter is journaled in the bearing 34 formed on the bracket 35 which projects from the frame 12 and is prevented from moving 90 laterally by shoulders 36 on said shank, engaging the ends of said bearing. The remaining portion of said shaft extends through slots 37 and 38 in plates 39 and 40 respectively which are secured to opposite 95 ends of the bar 41 and is journaled in the collar 42 secured to the plate 39. In sockets formed in the plates 39 and 40 are spring actuated friction plungers 43 which press against the shaft 32. Anchored in the rib 100 44, are two rods 45 which extend through, guide and support the bar 41 and the plates 39 and 40.

On the portion of the shaft 32 between the plates 39 and 40 are threads 46, 47, 48 110

and 49, hereinafter described, on the upper half of which are threaded die blocks 50, 51, 52 and 53, respectively. Supported by the plates 39 and 40 and secured thereto, is the guiding bar 54 which extends through slots in the upper portions of said die blocks. Journaled in bearings on brackets 55 and 56 are shafts 57 and 58. (Figs. 4, 6 and 7). Fixed to the forward end of the shaft 57 is the pinion 59 which meshes with gear 60. Fixed to the forward end of the shaft 58 is pinion 61 which meshes with gear 62. Gears 60 and 62 are journaled on a stud 63 fixed in the bracket 55 and are adapted to be rotated independently of each other. Pivoted at one end on the stud 64 fixed to the gear 60 and at the other end on the stud 65 fixed to a reciprocating rod 66 is a link 67. Pivoted at one end on the stud 68 which is fixed to the gear 62 and extends through the slot 69 in gear 60 and pivoted at the other end on the stud 65 is the link 70. The rod 66 may extend through and be guided by the sliding block 71 which is supported by the bracket 72 and is provided with the handle 73. Secured to the shafts 57 and 58 are clamping plates 74 and 74, respectively, each of which is provided with a slot 75.

On opposite sides of the die blocks 50, 51, 52 and 53 are reciprocating carriages 76 and 77. Journaled in said carriages are shafts 78 and 79, respectively, the rear ends of which extend through the slots 80, in the rib 44. Near the central portions of said shafts are formed threads 82, 83, 84 and 85 which are in line with and correspond to the threads 46, 47, 48 and 49, respectively. Threaded on the upper half of said threads and opposite the die blocks 50, 51, 52 and 53 are blocks 86, 87, 88 and 89, respectively. Extending through slots in said blocks and fixed to the carriages 76 and 77 are guiding bars 90 and 91, respectively. On the inner sides of each of the blocks 86, 87, 88 and 89 is pivoted the lever 92, the upper end of which is provided with a slot 93 adapted to receive a hook *h*. The lower arms of said levers are adapted to be engaged by the upper ends of arms 94. The latter are secured to shafts 95 which are journaled in suitable bearings on the carriages 76 and 77. (Figs. 3 and 8.) As the mechanisms for actuating each of said shafts are identical, a description of the mechanism for operating one of them will suffice for both. On one end of said shaft is fixed the pinion 97 which meshes with the rack 98. The latter is fixed to block 99 which is adapted to slide in the socket 100 formed in the carriage 76. Said block is provided with the slot 101 which receives one end of the shaft 78. On the rear end of said block is fixed rod 102 which extends through bearing 103 and socket 104. On

said rod and between collar 105 and the inner end of said socket is the expansion spring 106. The outer end of said rod is adapted to engage one end of rod 107 which extends through and is guided by ears 108. The latter project from the frame 12 and said rod is provided with the collar 109 and the spring 110 which bears against said collar and one of said ears.

The carriages 76 and 77 are or may be supported and guided by ribs 111 which project from the frame 12 and the rib 44, by said frame, by the latter rib, and by the gibs 112 bolted to the two latter members. Said carriages are reciprocated simultaneously, but in opposite directions by the eccentrics 113, which are fixed to the main shaft 10, through the toggles 114, adjustable connecting rods 115, and eccentric straps 116. The toggles 116 consist of links 117, the ends of which are pivoted on pins 118 fixed to the rear of said carriages and on bolts 119 fixed to the block 120, and links 121, the ends of which are pivoted on the bolts 119 and on bolts 122 which extend through ears 123 projecting from the frame 12. The portions of said bolts which pass through the links 121 are eccentric to the remaining portions, so that by turning said bolt the distance which said carriages travel toward the center of the machine may be varied. Said bolts are provided with heads and nuts which when tightened prevent said bolts from turning. Connection is made between the connecting rods 115 and the blocks 120 by ball and socket joints 124, and the eccentrics 113 and the eccentric straps 116 are so formed that said straps may swing sufficiently to allow for the inward swinging of the links 121.

Fixed to the shaft 10 is cam 125 which actuates an elbow lever 126 through cam roll 127. Said lever is pivoted at 128 on the bracket 129, and its lower arm is provided with pin 130 which engages lugs 131 on rack 132. The latter is adapted to slide on the bed 133 formed on the frame 12, and is in mesh with pinion 134 which is fixed to shaft 135. The latter is journaled in brackets 136 on the frame 12 and near its ends are fixed gears 137 and 138 which mesh with racks 139 and 140, respectively. One end of the former rack extends through the cross bar 141 and is supported and guided by bracket 142 which extends up from the frame 12, and the other end of said rod is fixed to the cross-bar 143. Extending through and fixed to the ends of said cross-bars and supported and guided by the bracket 142 and the similar bracket 144, are rods 145. On said rods, and bearing against the cross bar 141 and the bracket 144 are springs 146. It will be understood that the raised part 147 of the cam 125 during its rotation, will, through the cam roll 127, elbow 130

lever 126, pin 130 and lugs 131, move the rack 132 back from the position shown in Fig. 4 and that said movement of said rack will also move back the racks 139 and 140 against the action of the springs 146, through the rotation of the pinion 134, shaft 135, gears 137 and 138, respectively. When said raised part of the cam has passed the cam roll 127 said racks and other parts actuated by said cam are brought back to their initial position by the action of the springs 146. (Figs. 1, 4 and 5). On both vertical sides of the forward half of the rack 140 are teeth 148 which mesh with pinions 149 fixed to vertical shafts 150 and 151 which are journaled in the rib 44. On the upper ends of said shafts are fixed pinions 152 and 153, meshing respectively with racks 154 and 155. The ends of said racks extend into and are guided by brackets 155^a which are fast to the frame 12. (Figs. 1 and 4). As the mechanisms operated by both of said racks are identical, a description of the mechanisms operated by rack 154 will suffice for both. Fixed respectively to the top and bottom of said rack are flat rods 156 and 157, the inner ends of which overlap. (Figs. 1, 4 and 8). The outer edges of said rods are in contact with the inner faces of the four vertical raceways 158. The slot 159 in each raceway is substantially a continuation of the slot 93, hereinbefore described, and the lower end of each raceway is held in place by its pin 160, fixed to the rear of said end and extending through a lug 161 fixed to each block 86, 87, 88 and 89. On the upper end of each of said raceways is formed the semi cylindrical hub 162 which is pivoted between a bearing in the beam 163 and the short shaft 164. Above each of said raceways 158 is a raceway 165 which consists of a stationary semi cylindrical hub 166, a slot 167, which is a continuation of the slot 159, and an inclined rod 168 which leads into the slot 167. (Figs. 8 and 9.) The hooks *h* are fed onto and straddle the rod 168 in any suitable manner and slide down into the slot 167. As the hooks slide down said slot, one of their back edges strikes a projection 169 which causes the hooks to move so that their backs are substantially in a horizontal position. The hooks slide down the raceways 158 until they are stopped by the rods 156 and 157. When said rods move in the direction of the arrow shown in Fig. 8, the lowest hook on each raceway will slide down into its slot 93 as the end of the rod 157 passes said hook. In the operation of the machine a hook is fed into each of the slots 93 as hereinbefore described and the shaft 32 is pulled outwardly by hand until the plate 39 strikes stops 170 fixed to the rods 45. The portions of the shoe upper *s* to which the hooks are to be fastened are placed against dies 511 which are in the die blocks 51, 52, 53 and 54. To assist in placing the shoe upper in said position there are gage plates 171 fixed to the top of each die block, in such a position that when the top edges of the shoe upper are placed against said plates, the shoe upper is in the correct position to receive the hooks. The clamping plates 74 and 74 are then swung down, by mechanisms hereinbefore described, which will clamp the shoe upper firmly against said die blocks. (Figs. 6 and 7). The shaft 32 is then pushed inwardly until it is stopped by the plate 40 striking the rib 44. During the latter part of said inward movement, the end of said shaft strikes the set screw 31 which forces the arm 28, to which it is attached, to swing backwardly whereby through the pin 26, spring 27, and lever 22 will lift the arm 19 out of engagement with the plunger 16, allowing the latter to slide into engagement with one of the sockets 14 in the driving pulley 13 thereby forcing the main shaft 10 to rotate. The rotation of said shaft forces the carriages, through mechanism hereinbefore described, to slide toward the center of the machine which forces the hooks *h* to pierce the shoe upper and be set thereto by the dies 511, cooperating with the upper ends of the levers 92. It will be understood that this single operation sets both rows of hooks. Said movement of said carriages allows the springs 106 to move the racks 98 in the opposite direction, through mechanism hereinbefore described, which, through the pinions 97, shafts 95 and 96, swings the arms 94 out of engagement with the lever 92. At the start of the return movement of said carriages the levers 92, being now free to swing, disengage from the hooks *h*, and are then returned to their upright position by the arms 94. Near the start of the rotation of the main shaft 10 the lug 24 strikes the end of the arm 23 which rocks the lever 22 out of engagement with the pin 26 which allows the upper arm of the lever 19 to drop by gravity on to the clutch member 15, so that at the completion of one revolution of said main shaft, the cam surface 18 has engaged the cam surface 17 which effects the sliding of the plunger 16 out of engagement with its driving pulley 13. Said main shaft being deprived of its driving power, automatically comes to rest on the completion of one revolution. Immediately after said main shaft comes to rest which, of course, has also returned said carriages to their initial position, the rods 156 and 157, by the action of the springs 146 through mechanism hereinbefore described, allow each of the lowest hooks *h*, in the raceways 158, to drop down into the slots 93. The shaft 32 may then be pulled out and the clamping plates 74, 74

swung out of engagement with the shoe upper, so that the shoe upper may be removed and another applied. (Figs. 6 and 7).

The miter gear 33 meshes with miter gears 172 and 173 which are fixed on shafts 174 and 175, respectively, journaled in brackets 176. Mounted on said shafts are miter gears 177 and 178, respectively, which are adapted to be reciprocated independently of and to be rotated by said shafts. The shanks of the latter gears are journaled in bearings 179 on the rear ends of brackets 180 and 181. On the forward ends of said brackets are bearings 182, in which the shafts 78 and 79 are journaled. On the rear end of said shafts are fixed miter gears 183 and 184 which mesh with the miter gears 177 and 178, respectively. It will be understood from the foregoing, as all of said miter gears are the same size, that by rotating the shaft 32 the same amount of rotation will be imparted to the shafts 78 and 79 and that the miter gears 177 and 178 will reciprocate with the carriages 76 and 79. (Figs. 1 and 4). The threads 46, 47, 48 and 49 are so constructed that when they are rotated, the die blocks 50, 51, 52 and 53 will, although moved, keep the same relative distance apart, *i. e.*, the die blocks 50 and 53 will travel twice the distance as the die blocks 51 and 52. The edge of each portion of the upper to which the hooks are set, is approximately in the circumference of a circle and it is of course desirable to have the center of each hook in the circumference of a circle struck from the same center. The radius of said circle varies with the size of the upper. It will be seen from Fig. 4 that the dies 511 are in the circumference of a circle and that the threads 46 and 49 taper sufficiently, that by rotating the shaft 32, the radius of the circumference in which they are in and the distance which they are apart will vary in the same proportion as the radius of the circumference in which the hooks should be set in the upper, and the size of the upper. As the threads 82, 83, 84 and 85 on the shafts 78 and 79 correspond to and rotate with the threads 46, 47, 48 and 49 the slots 93 will always be in line with said dies.

In order to set the machine for any given size upper, a disk 185 is fixed to the shaft 32 and is provided with sockets 186 which are adapted to receive the spring actuated plunger 187 contained in a socket in the collar 42. Each of said sockets is for a particular size shoe upper, so that when said plunger engages a socket, the die blocks are moved into the correct position to receive the size shoe upper, represented by said socket.

Having thus described my invention I claim as new and desire to secure by Letters Patent.

1. A hook setting machine of the nature described comprising a series of laterally ex-

tending dies adjustably mounted, means for adjusting certain of said dies vertically relative to their associated dies, and a coöperating series of hook setting devices.

2. A hook setting machine of the nature 70 described comprising a series of laterally extending dies adjustably mounted, means for adjusting all of said dies relative to their spacing and for adjusting certain of said dies vertically, and a coöperating series of 75 hook setting devices.

3. A hook setting machine of the nature described comprising a series of laterally extending dies adjustably mounted, means for adjusting said dies relative to their spacing, 80 and a coöperating series of adjustable hook setting devices.

4. A hook setting machine of the nature described comprising a series of laterally extending dies slidably mounted for adjustment, means for effecting a right line movement of certain of said dies, means for moving certain other of said dies relative to such right line movement, and hook setting devices coöperating with said dies. 90

5. A hook setting machine of the nature described comprising a series of laterally extending dies mounted for movement to adjust said dies to the conformation, approximately, of various sizes of shoe uppers, 95 means for moving said dies, and hook setting devices coöperating with said dies.

6. A hook setting machine of the nature described comprising a series of laterally extending dies mounted for movement to adjust said dies to the conformation, approximately, of various shoe uppers, means operating simultaneously on all of said dies for effecting such adjustment, and hook setting devices coöperating with said dies. 100

7. A hook setting machine of the nature described comprising two series of movably mounted die members having oppositely extending dies, means for adjustably moving said die members, and two series of hook setting devices coöperating with said dies. 110

8. A hook setting machine of the nature described comprising a main resistance member, two series of dies movably mounted and bearing against said resistance member, 115 means for adjusting said dies, and coöperating hook setting devices.

9. A hook setting machine of the nature described comprising a main resistance member, two series of dies movably mounted 120 and bearing against said resistance member, means for adjustably moving said dies, in directions longitudinal of said resistance member to space said dies, and coöperating hook setting devices.

10. A hook setting machine of the nature described comprising a main resistance member, two series of dies movably mounted and bearing against said resistance member, means for moving all of said dies in direc- 13

- tions longitudinal of said resistance member and for moving certain of said dies in directions transversely of said resistance member, and coöperating hook setting devices.
- 5 11. A hook setting machine of the nature described comprising a series of die members movably mounted, screw members rotatably mounted and engaged with said die members, the periphery of the end portions 10 of said screws being conical in shape, and coöperating hook setting devices.
12. A hook setting machine of the nature described comprising a series of die members movably mounted, screws rotatably 15 mounted and in engagement with said die members, the screws engaged with the end die members being tapered and having respectively right and left hand threads and the screws engaged with the central die 20 members having respectively right and left hand threads, and coöperating hook setting members.
13. A hook setting machine of the nature described comprising a series of die members 25 movably mounted, means for adjustably moving said members simultaneously relative to spacing and to approximate shape of various sizes of shoe uppers, and coöperating hook setting devices.
- 30 14. A hook setting machine of the nature described comprising a series of die members movably mounted, means for adjustably moving said members simultaneously relative to spacing and to approximate shape 35 of various sizes of shoe uppers, a rotary gage device for operating said adjusting means, and coöperating hook setting devices.
15. A hook setting machine of the nature described comprising two series of die members 40 movably mounted, means for adjustably moving the respective die members of both of said series in unison relative to spacing and to approximate shape of various sizes of shoe uppers, and coöperating hook 45 setting devices.
16. A hook setting machine of the nature described comprising two series of die members movably mounted, means for adjustably moving the respective die members of both of said series in unison relative to spacing and approximate shape of various sizes of shoe uppers, a single gage device for determining the movement of such adjusting means, and coöperating hook setting devices.
- 50 17. A hook setting machine of the nature described comprising two series of oppositely facing dies, clamping plates pivotally mounted to swing toward said dies and having slots with which said dies are in registry, means for operating said clamping plates, and coöperating hook setting devices.
- 60 18. A hook setting machine of the nature described comprising a carriage slidably 65 mounted, die members movable with said carriage and relatively adjustable, means movable with said carriage for holding a shoe upper in position, means for operating said holding means, means for operating said carriage, and coöperating hook setting 70 devices.
19. A hook setting machine of the nature described comprising two series of oppositely facing and operating hook setting devices mounted for adjustment, and means 75 for adjusting said devices.
20. A hook setting machine of the nature described comprising two series of oppositely facing and operating hook setting devices mounted for adjustment, and means 80 for adjusting all of said devices simultaneously.
21. A hook setting machine of the nature described comprising two series of oppositely facing and operating hook setting devices mounted for adjustment as to spacing 85 and as to the line in which their hooks are to be set, and means for simultaneously adjusting all of said devices.
22. A hook setting machine of the nature 90 described comprising a series of die members adjustably mounted and having oppositely facing dies, two series of oppositely operating adjustable hook setting devices coöperating with said dies, and means for 95 adjusting said die members and said hook setting devices.
23. A hook setting machine of the nature described comprising a series of die members adjustably mounted and having oppositely facing dies, two series of oppositely operating adjustable hook setting devices 100 coöperating with said dies, and means for adjusting all of said die members and hook setting devices simultaneously. 105
24. A hook setting machine of the nature described comprising a carriage, a series of die members adjustably mounted thereon and having oppositely extending dies, means for adjusting said die members, two series 110 of oppositely operating adjustable hook setting devices coöperating with said dies, means for adjusting said devices, and connections between all of said adjusting means whereby they may operate in unison. 115
25. A hook setting machine of the nature described comprising a series of die members adjustably mounted and having oppositely extending dies, a rotatable adjusting screw having threads engaging said die members, two series of oppositely operating adjustable hook setting devices, screws having threads engaged with the respective hook setting devices, and connections between all of said screws. 120
26. A hook setting machine of the nature described comprising means for sustaining a shoe upper, dies bearing respectively against the inner surfaces of both of the edge portions of said upper when so sustained and 130

- hook setting devices coöperating with said dies.
27. A hook setting machine of the nature described comprising means for sustaining two sides of a shoe upper with their edges extending in the same general direction, and two lacing hook carriers delivering to said upper from opposite directions.
28. A hook setting machine of the nature described comprising means for sustaining two sides of a shoe upper with their edges extending in the same general direction, two lacing hook carriers delivering to said upper from opposite directions, and means co-operating with said carriers to set said lacing hooks.
29. A hook setting machine of the nature described comprising means for sustaining two sides of a shoe upper with their edges extending in the same general direction, two series of lacing hook carrying devices delivering to said upper from opposite directions, means coöperating with said devices to set said lacing hooks, and means for operating said hook carrying devices.
30. A hook setting machine of the nature described comprising means for sustaining both edges of a shoe upper in a vertical position, coöperating hook setting devices one of which is a hook carrier pivotally mounted and movable toward said upper in a horizontal path, and releasable means for positively swinging said hook carrier to a vertical position at a point in its movement.
31. A hook setting machine of the nature described comprising two series of dies facing in opposite directions, and two series of coöperating hook setting devices having hook carriers movable toward and from said dies and having hook releasing movements.
32. A hook setting machine of the nature described comprising two series of dies facing in opposite directions, two series of co-operating hook setting devices having hook carriers, movably mounted carriages for said hook setting devices, and mechanism operating said carriages of both series in unison.
33. A hook setting machine of the nature described comprising two series of dies facing in opposite directions, two series of co-operating hook setting devices having releasable hook carriers, movably mounted carriages for said hook setting devices, mechanism for operating all of said carriages in unison toward and from said dies, and means operating at the initial retractive movement of said carriages to release said hook carriers.
34. A hook setting machine of the nature described comprising two series of dies facing in opposite directions, two series of co-operating hook setting devices having pivoted hook carriers, movably mounted carriages for said hook setting devices, pivoted members for holding said hook carriers in upright positions, means for operating said pivoted members to release said hooks, and means for operating said carriages in unison.
35. A hook setting machine of the nature described comprising two series of dies facing in opposite directions, two carriages slidably mounted to move toward and from said dies, coöperating hook setting devices mounted independently on said carriages and having hook carriers, means for moving said carriages in unison, and releasable means for sustaining said hook carriers when said carriages are in the retracted position.
36. A hook setting machine of the nature described comprising two series of adjustable dies facing in opposite directions, two carriages movable toward and from said dies, means for moving said carriages, a series of coöperating hook setting devices adjustably mounted on each of said carriages, adjusting means respectively for said dies and for the hook setting devices, and connections between said several adjusting means whereby said dies and said hook setting devices may be adjusted in unison.
37. A hook setting machine of the nature described comprising a series of die members adjustably mounted and having oppositely facing dies, a rotary screw adjusting means for said dies, carriages movable toward and from said dies, coöperating series of hook setting devices adjustably mounted on said carriages, rotary screw adjusting means for said hook setting devices, means movable with said carriages for actuating their adjusting screws, and means for transmitting motion from the die adjusting screw to said actuating means of the hook setting device adjusting screws.
38. A hook setting machine of the nature described comprising a series of die members adjustably mounted and having oppositely facing dies, rotary means for adjusting said members, a pair of carriages slidably toward and from said dies, series of coöperating hook setting devices adjustably mounted on said carriages, rotary means on said carriages for adjusting their related hook setting devices, gears on all of said rotary means, shafts having gears driven by the gear of the die member adjuster, and gears slidably mounted on said shafts and operated thereby, said latter gears engaged with said gears of the hook setting device adjusters.
39. A hook setting machine of the nature described comprising a series of oppositely facing dies, a pair of carriages slidably mounted with respect to said dies, coöperating hook setting devices mounted on said carriages, pairs of toggle links located between said carriages and fixed parts of the machine, a main shaft, eccentrics on said

shaft, and rods operatively connected with said toggle links and operated by said eccentrics to effect the movement of said links to move said carriages toward said dies.

5 40. A hook setting machine of the nature described comprising a series of dies extending laterally, a series of hook supplies delivering at points spaced laterally, from said dies, coöperating hook setting devices having pivoted hook receivers and carriers, and means for bringing said hook receivers into registry with said hook supplies at times.

10 41. A hook setting machine of the nature described comprising two series of dies extending laterally, carriages movable toward said dies, hook setting devices on said carriages, and having pivoted hook carriers, means mounted on said carriages for swinging said hook carriers, and two series of 20 hook delivery ways spaced laterally from said dies and having their delivery ends located at points above said carriages whereby said hook receivers may be brought into registry with said ways when said carriages 25 are in their retracted positions.

42. A hook setting machine of the nature described comprising a pair of carriages slidably toward and from each other, hook setting members adjustably mounted, for 30 spacing, on said carriages and having pivoted hook carriers, actuators mounted on said carriages and in slidable engagement with said hook carriers, and means for effecting the adjustment of said hook carriers 35 of both carriages in unison.

43. A hook setting machine of the nature described comprising a pair of carriages slidably toward and from each other, hook setting members adjustably mounted, for 40 spacing, on said carriages, rotary screw adjusting means for said carriages, means for operating said adjusting means of both carriages in unison, hook carriers pivotally mounted on said carriages, a shaft journaled 45 in bearings of said carriage, members on said shaft and in slidable engagement with said hook carriers, means for partially rotating said shaft, and means for operating said carriages.

50 44. A hook setting machine of the nature described comprising coöperating organized means for sustaining both edges of a shoe upper in vertical operative position, means for delivering two series of lacing hooks approximately simultaneously to said edges and setting said hooks, and means for simultaneously releasing all of said hooks when so set.

60 45. A hook setting machine of the nature described comprising coöperating organized means having relative movement for sustaining both edges of a shoe upper in vertical operative position, means for delivering lac-

ing hooks to both of said edges approximately simultaneously, and setting said 65 hooks, and means for releasing said hooks when so set, the movement of said upper sustaining means carrying its upper to and from the operative position.

46. A hook setting machine of the nature 70 described comprising coöperating organized adjustable mechanism having relative movement for sustaining both edges of a shoe upper in vertical operative position, and means for delivering lacing hooks approximately simultaneously to both of said edges and setting said hooks in the material of 75 said edges, said mechanism including means for simultaneously adjusting all of said coöperating hook setting means simultaneously.

47. A hook setting machine of the nature described comprising a pair of carriages slidably mounted, hook setting and carrying devices mounted on said carriages, a main 80 shaft, mechanism operated by the rotation of said main shaft to effect the movement of said carriages toward each other, a driving pulley loose on said shaft, clutch mechanism for connecting said pulley with said shaft, 85 a third carriage slidably mounted between said pair of carriages and having means for positioning a shoe upper, and mechanism operated by said shoe upper carriage for effecting the operation of said clutch mechanism to connect said driving pulley and 90 main shaft.

48. A hook setting machine of the nature described comprising a pair of carriages slidably mounted, hook setting and carrying 100 devices mounted on said carriages, a main shaft, mechanism operated by the rotation of said main shaft to effect the movement of said carriages toward each other, a driving pulley loose on said shaft, a clutch connection for said pulley on said shaft, clutch actuating mechanism including a tripper, a work holder carriage slidable between said hook setting carriages, and a member mounted in said work holder carriage and adapted 105 to engage and operate said tripper when said work holder carriage reaches the operative 110 position.

49. A hook setting machine comprising two series of movable dies of which one 115 series extends oppositely to the other series, two series of coöperating hook setting devices movably mounted, a series of adjusting screws for said dies, and for said hook setting devices, and means for rotating said 120 screws simultaneously.

EDMUND CURRAN.
